UNITED STATES PATENT OFFICE.

CHARLES GILBERT HAWLEY, OF CHICAGO, ILLINOIS.

HIGH-PRESSURE STEAM BOILER.

Application filed March 15, 1924. Serial No. 699,592.

- This invention relates to steam boilers and their furnaces, and more particularly to that type of boiler in which due regard is given to proper relationship and proportions between the heat absorbing surfaces and elements and the fire in such manner as to secure maximum efficiency with boiler elements of minimum size. These results are obtained by the provision of a minor extent of heat absorbing circulating elements so proportioned and disposed as to take advantage of the radiant heat of the flames of a long flaming fire and permit such flames to rise to substantially full or natural maturity, or without suppression to develop the maximum radiant heat effect, together with a major extent of heat absorbing elements so positioned and proportioned as to be capable of economically absorbing or accepting substantially all of the radiant heat from the residual gases leaving the chamber in which the radiant heat is obtained and thereby causing the waste gases to enter the stack at as near steam temperature as desired.
- A number of forms of boiler for producing the effects thus briefly described are shown and described in my prior patent for steam boilers, No. 1,486,888 granted March 18, 1924, to which reference may be had for a more complete description and discussion if necessary. For the purposes of this application it is sufficient to say that the results of the invention may be obtained in practically any form or type of boiler, so long as its heat absorbing circulating elements are properly proportioned and positioned with reference to the fire and flames.
- The present application has particular relation to a boiler of steeped form, in which the heat absorbing circulating tubes of major extent for absorbing the convected heat are superposed upon or lie above the chamber in which the radiant heat is most efficiently developed and transmitted to the heat absorbing circulating elements of minor extent, and which boiler may also conveniently be built in sectional form, with improved header members of simple and efficient design and of a size convenient for transportation and erection purposes. The boiler also is well adapted for efficient firing and does away with any necessity of large heavy drums such as are usually necessary on high pressure steam boilers, and on the contrary may embody relatively small drums and other heat absorbing elements and still develop the necessary high pressures to meet the modern trend of boiler practice. The arrangement of the heat absorbing circulating tubes is convenient for erection, renewal and repair purposes or for insertion, removal or repair of arches or baffle walls and also provides the necessary available space for super-heater elements, where such are used. In addition the circulating elements are so disposed and arranged as to provide for rapid separation of steam with violent coursing of the water over the surfaces with which it contacts to fully protect the same, all within a minimum of space and with maximum steaming capacity for the surface area, number and weight of tubes and other boiler elements utilized.
- In the drawings, Fig. 1 represents a sectional elevation on the line 1—1, Fig. 2, through one form of boiler embodying the invention; Fig. 2 is a sectional elevation on the line 2—2, Fig. 1; and Fig. 3 is a sectional plan view on the line 3—3, Fig. 2.
- The embodiment of the invention which is shown in the drawings, is a high pressure steam boiler of large size and great capacity, intended for use above a furnace of maximum capacity, for the development of large volumes of steam at the high pressures now called for, and at properly reduced costs of fuel, attendance and maintenance.
- No stay bolted parts are included in the pressure vessel or boiler proper. Instead it is entirely composed of water and steam tubes and comparatively small water and steam drums to which the tubes are connected. As a whole, the pressure vessel thus composed of drums and tubes is of substantially rectangular cross section (see Fig. 3) and is of very considerable height. The height is an element of assurance in the matter of the proper continuity of combustion in the tall chamber 3 and for the rest the matter of height has a direct relation to the amount of floor space which the boiler occupies, it being deemed better and indeed, being better, to extend the boiler vertically than horizontally.
- For sake of freedom of expansion and contraction throughout the boiler it is suspended from its top, as upon the cross beams A. The top drums 10 and 11 are extended in order that they may rest upon the beams A. All the other parts of the boiler hang from the drums 10 and 11. The particular parts and

their relations will be described hereafter. Meantime it is to be understood that the beams or girders A are, in effect, parts of the general building structure, which includes the corner columns B, and the several floor structures C. Generally the boiler towers through several floors of the boiler house; and, its several parts are conveniently accessible from the different floors C thereof, as will be apparent from the drawings. Various doors D, are provided in the casing of the boiler to afford access to the interior thereof. As a rule the boiler proper directly carries its four enclosing walls E, of tile or brick. These are applied against and between the adjacent upright tubes of the boiler, the outermost of which tubes are intentionally designed to aid in supporting the refractory casing. The casing tiles are enclosed by a metal casing, F, which extends from top to bottom of the boiler; serving also to prevent the leakage of air into, or gas from, the boiler gas passages. The ends of the drums 4, 6, 7, 10 and 11 pierce the metal jacket so that they shall be accessible; and assist in supporting the jacket. To avoid the necessity of heavily loading the suspended boiler with fire brick and other insulating tiles, the lower part of the boiler, where the heat of the fire is most intense, is provided with comparatively thin walls E, little thicker than needed to protect the metal casing F. The heat which would otherwise be lost through these thin walls is recovered by means of an open topped air jacket, G, which surrounds the lower half of the boiler and from which the hot air is exhausted into the fire chamber (1) of the boiler, as through holes g' in the sides of the fire chamber. It should be explained that the metal jacket F, is loosely joined to the top of the underlying fire chamber, I, and no parts are present to prevent the free expansion and contraction of the boiler with respect to the refractory walled fire chamber. Because of the small scale upon which Figs. 1 and 2 are drawn, the water tubes are represented by single lines; however, a complete understanding thereof is afforded by Fig. 3 which is upon a larger scale. Generally, the dimensions of the boiler and its setting will be clearly apparent when it is understood that on the scale shown the drums 4, 7 and 11 are two feet in diameter; just large enough to admit a workman for the purpose of installing or repairing the connected tubes. As a matter of course all drums are provided with manholes and cover plates in their ends. The water level of this boiler is maintained about half way up in the upper drums 10 and 11. No attempt has been made to show the ordinary boiler accessories, such as gages, blow-off connections and the like, all of which are assumed to be present. The boiler shown comprises a suitable frame work and setting, marked generally 1,

of any suitable form. Firing means of any type or description may be used for either liquid, gaseous or solid fuel. For convenience of illustration, the drawings show the boiler as fired from opposite sides by chain grates 2 cooperating with the ash receiving pit or hopper 3, although it will, of course, be understood that the boiler may be fired from any one or more directions.

The flames from the fire on said grate rise to substantially full or natural maturity in a relatively tall chamber 3, where the radiant heat of the flaming gases is passed to and accepted by radiant heat absorbing elements, and the hot gases leaving the combustion chamber 3 rise to and pass through a convected heat absorbing boiler portion superposed upon or lying above the radiant heat absorbing portion.

The radiant heat absorbing portion of the boiler, in the specific form shown, comprises a series of oppositely disposed horizontally extending header members 4, shown as drums, lying along the four sides near the bottom of the combustion chamber 3, each of the several drums overlapping the end of the next adjacent drum. This enables the four drums to be duplicate units available for quantity production. Neighboring drums may be connected at their ends in any suitable manner, such as by tubes 5. Above said drums 4 are located a series of parallel horizontally extending inner intermediate drums 6, three of which are shown, and smaller outer intermediate drums 7, all at approximately the same level near the top of the combustion chamber 3, the several drums being cross-connected at intervals by the tubes 8. These parallel horizontal intermediate drums are connected to the bottom opposed parallel header members or drums 4 by a series of rising heat absorbing elements or tubes 9, the major portions of which are vertical, but which at their lower ends are bent laterally for connection to the various ones of the lower drums 4, as shown.

The convected heat absorbing portion of the boiler is in sectional form and includes the drums 6, 7 before referred to, and a like series of parallel horizontally disposed upper drums 10, 11 cross-connected at intervals by the tubes 12, and connected as units for the purpose of sectional construction with the intermediate drums 6, 7 by parallel vertically extending convected heat absorbing tubes 13. The smaller upper drums 11, at the sides of the boiler, maybe connected to the intermediate side drums 7 by return tubes 14.

All intermediate drums 6 and 7 are connected to the bottom drums 4 by return tubes 15; some of these tubes being directly presented to the luminous and non-luminous hot gases and others imbedded in the setting walls, as may be readily understood. Obviously the drums 7 and two drums 4 lie in par-

allel lines so that each drum 4 may be easily connected with its elevated drum 7 by means of the tubes 15. The other pair of drums 4, being relatively perpendicular to the drums 6 and 7, require that the tubes 15 which rise from the bottom drums, 4, shall have their upper ends bent and connected with the bottoms of respective drums 6 and 7 after the manner followed in the arrangement of the tubes 9 in Fig. 1. Thus the group of drums 4 which frames the top of the furnace chamber is suspended from and connected with the elevated group of drums 6 and 7. Thin firebrick walls extending from the drums 4 upward to the elevated group, are attached to and serve to imbed the outermost return tubes 15, a substantial wall structure resulting.

The radiant heat absorbing tubes 9 are of minor extent and the convected heat absorbing tubes 13 are of major extent. That is to say, the radiant heat absorbing tubes 9 are of a size and number and are so distributed or placed as to permit the flames in chamber 3 to rise to substantially full or natural maturity therein without material suppression or extinguishment, their duty being to absorb or accept radiant heat from the flame or luminous gases without choking down the flame. They are therefore fewer in number, or more accurately, their total available heat absorbing surface is materially less than that of the convected heat absorbing circulating tubes 13, the duty of which is to accept or absorb convected heat carried to them by the current of hot gases issuing from the upper portion of chamber 3 in which the radiant heat effect is predominant. The radiant heat absorbing tubes should have ample surface for accepting or absorbing all available radiant heat. Indeed, their available heat absorbing surface should be a little more, if anything, than necessary for this purpose, chiefly for the reason that radiant heat is propagated according to the principles of light, while convected heat is absorbed or accepted from hot gas by a boiler element by actual contact of the hot gas therewith.

For the latter reason the major extent of convected heat absorbing tubes of relatively larger number or total surface area are therefore relatively closely spaced from each other to distribute the heat absorbing surface and secure contact with as much of the non-luminous gas as possible, while the minor extent of radiant heat absorbing tubes are relatively widely spaced, one suitable arrangement for the purpose being a distribution of said tubes in rows lying in vertical planes across the combustion chamber, the wide avenues between said rows permitting the flames to rise to substantially natural maturity without material suppression or extinguishment. This construction enables all of the several drums or header members to be of relatively small size and diameter and enables them to be made of

relatively light gauge material with a consequent reduction in weight and in the cost for labor and material, and in convenient form for quantity production, ease of assembling, repair or replacement, and conserving space in snipping. These lighter weight drums also enable the high pressures toward which modern boiler practice trends, to be secured without resort to heavy materials, as has been usual.

This arrangement of radiant and convected heat absorbing tubes connecting three sets of lower, intermediate and upper header members, with the necessary return tubes, provides a violent coursing or circulation of the water in the boiler with rapid movement over all surfaces in contact with the flame or hot gases and thereby protects the same. The setting may also be brought up inwardly of the lower header members 4 where the sediment collects, as at 16, to protect these sediment collecting portions of the boiler elements.

Where desired, the boiler may also be provided with accessories, such as a drier, represented at 17, and comprising horizontally extending tubes connecting the two steam domes or drums 18 and 19 extending transversely to the drums 10, 11 at the front and rear of the boiler, one of said drums, such as drum 18 being connected at intervals to the various header members 10, 11 by the tubes 20. The steam issuing from drum 19 may be led by pipe 21 to a suitable super-heater represented conventionally at 22, and the several sections of which are located in avenues between rows of the vertical tubes of the several units or sections of the convected heat absorbing tubes 13 of the boiler. Emerging from the super-heater, the steam passes to the line pipe 23.

Few if any, gas baffles are required in this boiler. However when the superheater sections 22 are not used those spaces should contain small cross baffles or floors (not shown); and obviously the various tubes provide proper support for almost any sort of baffles. As a rule however, the apparatus may be regarded as a single pass boiler with all the advantages attendant upon dispensing with annoying baffles.

Claims:

1. A steam boiler of tubular construction throughout and hence adapted to sustain high pressures, and, bodily suspended above a suitable furnace chamber; said boiler being characterized by a horizontally positioned group of water drums which frame the top of said chamber, in combination with horizontally spaced return tubes rising from all said drums and framing a fire chamber which extends above said furnace chamber, brick walls supported by said drums and tubes and extending to the tops of the latter, a horizontally positioned group of parallel steam-and-water drums elevated above the first group and wherewith the upper ends

of respective return tubes communicate, said elevated group supporting the lower drums, tubes and brick.

2. A steam boiler of tubular construction throughout and hence adapted to sustain high pressures, and, bodily suspended above a suitable furnace chamber; said boiler being characterized by a horizontally positioned group of water drums which frame the top of said chamber, in combination with horizontally spaced return tubes rising from all said drums and framing a fire chamber which extends above said furnace chamber, a horizontally positioned group of parallel steam-and-water drums elevated above the first

group and wherewith the upper ends of respective return tubes communicate, said upper group supporting the said tubes and the lower drums, vertically planular groups of radiant heat absorbing tubes connected with and depending from the bottoms of the drums intermediately positioned in the elevated group, and, the lower ends of the last mentioned tubes being extended laterally within said fire chamber and joined to respectively perpendicular drums in the lower group. 20 25

In testimony whereof I hereby affix my signature.

CHARLES GILBERT HAWLEY.
